[57] **CLAIM**

The ornamental design for a housing for a battery operated chainsaw, as shown and described.

DESCRIPTION

FIG. 1 comprises a perspective view, taken from the right and from the front, of one embodiment of a housing for a battery operated chainsaw according to the present invention;

FIG. 2 is a perspective view, taken from the left and from the rear, thereof;

FIG. 3 is a plan view thereof;

FIG. 4 is a right elevational view thereof;

FIG. 5 is a front elevational view thereof;

FIG. 6 is a rear elevational view thereof;

FIG. 7 is a left elevational view thereof; and,

FIG. 8 is a bottom elevational view thereof.

The broken lines showing a chainsaw blade are for illustrative purposes only and form no part of the claimed design.
